CORPORATION OF CALIFORNIA.

FRUIT CUTTING AND PITTING TABLE.

1,364,289.

Specification of Letters Patent.

Patented Jan. 4, 1921.

Application filed January 12, 1920. Serial No. 350,873.

To all whom it may concern:

Be it known that we, DAVID Low and WILLIAM H. GAVIN, citizens of the United States, the said Low residing at San Jose, 5 in the county of Santa Clara and State of California, and the said GAVIN residing at Santa Clara, county of Santa Clara, State of California, have invented certain new and useful Improvements in Fruit Cutting 10 and Pitting Tables, of which the following is a specification.

Our invention relates to work-tables of the type used in canneries for the cutting and pitting of fruit.

15 The object of our invention is to provide a table which enables the operator to work with the greatest possible convenience and speed, and which permits of ready and instant inspection and removal of the finished 20 product.

Although our table is particularly adapted for cutting and pitting fruit, such for example as peaches and apricots, it is to be understood that the invention is not restricted to such use, but is equally applicable 25 to tables for any other purposes which involve similar movements on the part of the operator.

Our table is adapted to be constructed as 30 a series of adjacent similar units, connected together or separate as may be desired, each unit forming a complete work-table for one operator. The following description, therefore, will be confined to one unit, it being 35 understood that any desired number of such units may be used, all having a common discharge conveyer, as will be later set forth.

With this in view the invention will now 40 be described in detail with reference to the accompanying drawings, wherein:

Figure 1 is a perspective view showing one complete work-table unit and a portion of an adjacent unit, certain parts being shown in dotted lines for the sake of clearness.

Fig. 2 is a transverse vertical section taken on the line 2—2 of Fig. 1.

Fig. 3 is a transverse vertical section taken on the line 3—3 of Fig. 1.

50 In the drawings, the reference numeral 1 designates suitable supporting legs which may be arranged in any desired manner. The top of the table, which is supported by

said legs 1, is divided into three adjacent sections, as shown in Fig. 1, a receiving section 2, a work section 3, and a discharge section 4. It is intended that the operator shall stand or sit in front of the central work section 3, having the receiving section 2 on his left and the discharge section 4 on 60 his right.

The receiving section 2 is provided with a pair of spaced guide rails, 5, preferably formed of angle iron, whose forward portions are tilted downwardly, as at 6, and a transversely disposed roller 6' is provided at the junction of the inclined and horizontal portions of said rails. Said rails are so spaced as to receive and form a track for the standard lug-boxes used in the plant for receiving and bringing in the un-cut fruit, said boxes being placed on said rails preferably by an attendant passing behind the table. The lug-box 7 containing the fruit which is being cut is drawn forward over the roller 6' on to the tilted portion 6 of said track, as shown in Figs. 1 and 2, to be within easy reach of the operator, and a second full box, not shown, can then be placed on the rear horizontal portion of said track. 75

The discharge section 4 is also provided with a track 8, Figs. 1 and 3, preferably formed of spaced angle irons, and upon this track rests a bottomless container or inspection cage 9. At the rear portion of said discharge section is a hopper 10 formed in the table top, leading into a discharge trough 11. A suitable conveyer, here shown as an endless belt 12, operates continuously 80 in the bottom of said trough. The trough 11 and the conveyer belt 12, positioned transversely of the table at the rear and below the top thereof, are common to all the units of 85

each series, and may or may not be supported by said units. In the form herewith illustrated, all units of a series are built together as one long structure, which supports the trough and the conveyer belt. The return run 13 of the conveyer belt is preferably positioned below the trough 11 and 90 carried upon suitable sheaves or rollers 14.

The operator removes the fruit from the box 7 with his left hand, cuts and pits it over the central section 3 of the table, allowing the pit to fall upon said central table 105 section, and deposits the cut fruit in the in-

spection cage 9 at his right, said cage then occupying a position at the front of the table section 4, whereby the table itself forms the bottom of the cage. When said cage is full, 5 or contains as much cut and pitted fruit as is desired, it is pushed rearwardly to a position in the center of the discharge section 4, and a second empty inspection cage is placed on the forward portion of said section 4. The fruit in the first cage is then 10 inspected by the proper attendant, and if found satisfactory said cage is by him moved over the hopper 10, as shown in Figs. 1 and 3, thus allowing the fruit to fall onto the 15 discharge conveyer 12, by means of which it is removed to any suitable place of deposit not shown in the drawings.

Thus the operator is constantly supplied with un-cut fruit at his left, and the cut 20 fruit is constantly removed from his right, so that he need not be delayed in his work to wait, either for a fresh supply or for the removal of the cut fruit. Moreover, the tracks 5 and 8 insure that the positions of 25 the fresh supply and the cut fruit container will always be the same, so that the operator is never confused by the necessity of reaching to different positions.

We claim:

30 1. A work-table for fruit-cutters having a work section and a discharge section with an aperture formed in one end thereof; spaced rails forming a track positioned upon the discharge section and straddling 35 said aperture; a bottomless container for receiving the cut fruit positioned upon the track of said discharge section and adapted to be moved into registry with said aperture for discharging the cut fruit therethrough; 40 and means for removing the cut fruit from beneath said aperture.

2. A work-table for fruit-cutters having a work section and a discharge section with an aperture formed in one end thereof; 45 spaced rails forming a track positioned upon the discharge section and straddling said aperture; a bottomless container for receiving the cut fruit positioned upon said track and adapted to be moved into registry with said aperture for discharging the cut fruit therethrough; a discharge trough positioned beneath said aperture; and conveyer 50 means within said trough for removing the cut fruit.

55 3. A work-table for fruit-cutters having a downwardly inclined receiving section adapted to support a container for the fruit to be cut, a work section, and a discharge section with an aperture formed in one end 60 thereof; spaced rails forming a track positioned upon the discharge section and straddling said aperture; a bottomless container for receiving the cut fruit positioned upon the track of said discharge section and 65 adapted to be moved into registry with said

aperture for discharging the cut fruit therethrough; and means for removing the cut fruit from beneath said aperture.

4. A work-table for fruit-cutting having a receiving section, a work section, and a discharge section with an aperture formed in one end thereof; spaced rails forming a track positioned upon the receiving section for supporting a container for the fruit to be cut, the forward portion being inclined 70 downwardly; spaced rails forming a track positioned upon the discharge section and straddling said aperture; a bottomless container for receiving the cut fruit positioned upon the track of said discharge section and 75 adapted to be moved into registry with said aperture for discharging the cut fruit therethrough; and means for removing the cut fruit from beneath said aperture.

5. A work-table for fruit-cutters having a 80 central work section with a receiving section on one side and a discharge section on the other side, said discharge section having an aperture formed in the rear portion thereof and said receiving section being downwardly 85 inclined at its forward portion; spaced rails forming a track positioned upon the receiving section for supporting containers for the fruit to be cut; spaced rails forming a track positioned upon the discharge section and 90 straddling said aperture; a bottomless container for receiving the cut fruit positioned upon the track of said discharge section and adapted to be moved into registry with said aperture for discharging the cut fruit therethrough; and means for removing the cut fruit from beneath said aperture.

6. A work-table for fruit-cutters comprising a series of spaced work sections separated by receiving and discharge sections, 95 there being a receiving section on one side of each work section and a discharge section on the other, and each discharge section having an aperture formed at the rear portion thereof; tracks positioned upon the receiving and discharge sections for supporting containers for the fruit, the tracks of the discharge sections straddling said apertures; bottomless containers for receiving the cut fruit positioned upon the tracks of 100 the discharge sections and adapted to be moved into registry with said apertures for discharging the cut fruit therethrough; a common discharge trough positioned beneath said apertures for receiving the cut 105 fruit therefrom; and conveyer means operating within said trough for removing the cut fruit.

7. A work-table for fruit-cutters having a discharge section with an aperture formed 110 in one portion thereof; and a bottomless container for receiving the cut fruit, said container normally resting upon the unapertured portion of said section and adapted to be moved thereon into registry with the 115

aperture therein, whereby the cut fruit is discharged through said aperture.

8. A work-table for fruit-cutters having a discharge section with an aperture formed in one portion thereof; a bottomless container for receiving the cut fruit, said container normally resting upon the unapertured portion of said section and adapted to be moved thereon into registry with the 10 aperture therein, whereby the cut-fruit is discharged through said aperture, and means underlying said aperture for receiving and removing the discharged fruit.
9. A work-table for fruit-cutters having 15 an inclined receiving section adapted to support a container for the fruit to be cut, a discharge section with an aperture formed in one portion thereof, and a work section lying between the receiving and the discharge sections; and a bottomless container 20 for receiving the cut fruit, said bottomless container normally resting upon the up-apertured portion of the discharge section and adapted to be moved thereon into registry 25 with the aperture therein, whereby the

cut fruit is discharged through said aperture.

10. A work-table for fruit-cutters having an inclined receiving section adapted to support a container for the fruit to be cut, a 30 discharge section with an aperture formed in one portion thereof, and a work section lying between the receiving and the discharge sections; a bottomless container for receiving the cut fruit, said bottomless container normally resting upon the unapertured portion of the discharge section and adapted to be moved thereon into registry with the aperture therein, whereby the cut fruit is discharged through said aperture; 40 and a traveling conveyer underlying said aperture, to receive and remove the cut fruit.

In testimony whereof we have signed our names to this specification in the presence of two subscribing witnesses.
